UNITED STATES PATENT OFFICE.

DAVID HAMILTON, OF GREENSBURG, PENNSYLVANIA.

VALVE.

1,175,258.

Specification of Letters Patent.

Patented Mar. 14, 1916.

Application filed February 25, 1915. Serial No. 10,530.

To all whom it may concern:

Be it known that I, DAVID HAMILTON, a citizen of the United States, residing at Greensburg, in the county of Westmoreland and State of Pennsylvania, have invented 5 certain new and useful Improvements in Valves; and I do declare the following to be a full, clear, and exact description of the invention, such as will enable others skilled in the art to which it appertains to make and use the same.

My invention relates broadly to improvements in valves and more particularly to those having vertical externally threaded 15 stems and nuts through which the stems are threaded, the main object of the invention being to provide simple and efficient lubricating means surrounding the stem directly below the nut, whereby the threads thereof 20 are lubricated at all times.

A further object is to provide a member supported by the valve casing and adapted to receive a packing ring for preventing the leakage of oil from the lubricating means.

Yet another object is to improve upon the general construction of devices of this character to such an extent as to provide a simple, strong and very efficient valve.

With the above objects in view, the invention consists of certain novel features of construction and combination herein described and claimed and shown in the drawings wherein:—

Figure 1 is a side elevation of a valve 35 constructed in accordance with my invention; Fig. 2 is a central vertical longitudinal section thereof with the lubricating device and the valve in active position; Fig. 3 is a detail perspective view of the parts 14 and 40 25; Fig. 4 is a horizontal section as seen along the plane of the line 4—4 of Fig. 2.

In these drawings, constituting a part of this application, the numeral 1 designates a horizontally disposed substantially cylindrical valve casing whose opposite ends are open and provided with polygonal external heads 2 for the reception of a wrench, while such ends are internally threaded as seen at 3 to provide for the attachment of inlet and 50 outlet pipes (not shown). As most clearly disclosed in Fig. 2, the center of the casing 1 is provided with what may well be termed a horizontal partition 4 which is provided with an opening 5 having two diameters, the 55 upper end of the opening being of greater diameter than the lower end thereof and

having its wall threaded to receive external threads on a removable valve seat or ring 6, the interior diameter of this ring being equal to the diameter of the lower end of the opening 5.

Formed upon the upper side of the casing 1 at a point directly above the partition 4, is an upright hollow boss 7 whose upper end is externally threaded as seen at 8, these 65 threads receiving similar threads formed on the inner side of a horizontally disposed ring 9 from which a pair of yoke arms 10 rise, these arms being extended inwardly at their upper ends and integrally joined to a 70 nut 11, this nut depending below its junction with the arms 10 and being here externally threaded as seen at 12.

The arms 10 are here shown as equipped with an annular stop shoulder 13 which is 75 formed integrally with the ring 9 and which bears against the top of a disk 14, this disk resting squarely upon the upper end of the hollow boss 7 and normally closing the latter. At its center, the disk 14 is provided 80 with a circular opening 15 which is vertically alined with but of less diameter than the opening 5, and on its upper side, said disk is equipped with a vertical annular flange 16 which is spaced outwardly a considerable distance from the opening 15, whereby to provide an annular pocket for 85 the reception of a packing ring 17.

As clearly disclosed in Figs. 2 and 3, the ring 17 snugly surrounds an upright cylindrical stem 18 whose upper end is externally threaded at 19 through the nut 11, while its lower end passes through the central opening 15 and terminates directly 90 above the removable seat or ring 6, at which point it is provided with a removable head 20, which retains in position an inverted cup-shaped ring 21, the inner side and upper end of this ring having a flange 22 contacting with the upper side of the head 100 95 as shown. With the parts in this position, a removable valve disk 23 having a reduced externally threaded boss, at its center is secured to said ring 22 by threading its boss into the lower end of the same, in which 105 position, the upper end of the boss contacts with the lower side of the head 20. The active or lower face of this disk 23 is here shown as of substantially a diameter equal to the diameter of the ring 6 with which 110 it coacts to obstruct communication between the two ends of the casing 1.

Hereinbefore, I have mentioned an oil cup and have described threads 12 on the lower end of the nut 11, it being evident from an inspection of the drawing, that 5 such threads receive similar threads which are formed on the interior of the annular wall of said cup, the latter being designated by the numeral 25 and having a reduced hollow boss or flange 26 which depends 10 from its lower side and normally projects a sufficient distance into the flange 16 to effectively compress the packing 17 therein. With the parts located in this manner, the cup 25 is adapted to be filled with oil, which 15 oil will then surround the threads on the stem, thus effectively lubricating the same at all times. When however, it is necessary to replenish the supply of oil in the cup, this may be done through an annular groove 20 25^a formed in the upper end of the nut 11, and through an upright groove 25^b which leads downwardly therefrom into the oil cup 25.

From the foregoing description, taken in 2 connection with the accompanying drawings, it will be seen that a very simple and 3 efficient lubricating device has been provided 4 for oiling the threads of the valve stem to allow it to be easily rotated to open and 5 close the valve, yet that the leakage of oil 6 from the oil-cup into the valve casing is 7 positively prevented by the provision of the 8 packing ring 17. It will further be seen 9 that no threaded connection which might 10 corrode, is provided between the plate or 11 disk 14 and the hollow boss 7, but that said 12 plate or disk is held in fluid tight contact 13 with the upper end of said boss by the ring 14 or shoulder 13 on the yoke, this being also 15 a rather important feature of the invention.

The stem, above described, may be 16 equipped with a hand wheel 40 as shown in 17 the drawings, but might well be provided 18 with other means for rotating it at will, 19 such hand wheel being preferable, however. 20

Copies of this patent may be obtained for five cents each, by addressing the "Commissioner of Patents, Washington, D. C."

I am aware, that numerous valves of the same general character hereinbefore described, have been previously put in use, but I am not aware that the details claimed by me as my invention, have heretofore been known to the art. 50

I claim:—

1. The combination with a valve having an upright externally threaded operating stem, and a nut through which said stem is 55 threaded, the lower end of said nut being provided with screw threads, of an oil-cup surrounding the stem directly below the nut and having screw threads engaging the threads thereon. 60

2. The combination with a valve having an upright externally threaded operating stem, a nut through which the stem is 65 threaded, and an oil cup surrounding the stem directly below the nut, said cup being 70 adjustable vertically, of an annular chamber surrounding the stem, a packing ring disposed in said chamber and contacting with the stem, and a flange depending from the oil-cup and bearing against said ring. 75

3. The combination with a valve having an upright externally threaded operating stem, a nut through which said stem is 75 threaded, said nut having external screw threads at its lower end, and an oil-cup surrounding the stem directly below the nut and having internal screw threads engaged with the threads thereon, of an annular chamber surrounding the stem directly below the oil-cup, a packing ring in said chamber 80 and contacting with the stem, and an annular flange depending from the oil cup and bearing against said ring. 85

In testimony whereof I have hereunto set my hand in presence of two subscribing witnesses.

DAVID HAMILTON.
